UNITED STATES PATENT OFFICE

99,412

DESIGN FOR A NAPKIN OR SIMILAR ARTICLE OF PAPER

Lewis F. Nelson, Kaukauna, Wis.

Application December 18, 1934, Serial No. 54,481

Term of patent 7 years

To all whom it may concern:

Be it known that I, Lewis F. Nelson, a citizen of the United States, residing at Kaukauna, in the county of Outagamie and State of Wisconsin, have invented a new, original, and ornamental Design for a Napkin or Similar Article of Paper, of which the following is a specification, reference being had to the accompanying drawing, forming part thereof.

Figure 1 is a plan view of substantially one-fourth of the napkin or similar article of paper outlined by dot and dash lines a—b—c, the other three-fourths being positioned in proper relation thereto to complete the article as indicated by the extensions beyond the quarter section of the indications; and

Fig. 2 is an enlarged detail showing of the checker-like depressions taken on the line 2—2 of Fig. 1, said depressions being an essential part of the design.

I claim:

The ornamental design for a napkin, or similar article of paper, as shown and described.

LEWIS F. NELSON.
